UNITED STATES PATENT OFFICE.

ALFRED L. ATHERTON, OF PITTSBURGH, PENNSYLVANIA, ASSIGNOR TO WESTINGHOUSE ELECTRIC & MANUFACTURING COMPANY, A CORPORATION OF PENNSYLVANIA.

REGULATING TRANSFORMER.

Application filed June 18, 1919. Serial No. 305,130.

To all whom it may concern:

Be it known that I, ALFRED L. ATHERTON, a citizen of the United States, and a resident of Pittsburgh, in the county of Allegheny and State of Pennsylvania, have invented a new and useful Improvement in Regulating Transformer, of which the following is a specification.

My invention relates to transformers and 10 it has particular relation to transformers which are adapted to regulate the current furnished thereby and which are commonly known as constant-current transformers.

In the accompanying drawing, Figure 1 15 is a top plan view of a transformer embodying my invention; Fig. 2 is a side view of the same transformer, partially in section and partially in elevation; Fig. 3 is a graph representing the operating conditions in a 20 transformer of my invention; Fig. 4 is a dia-grammatic showing of the primary and sec-ondary circuits of my transformer and illus-trates specifically the manner of connecting the secondary members and their associated 25 loads; and Figs. 5 and 6 are fragmentary views of a portion of the transformer illus-trated in Figs. 1 and 2.

One object of my invention is to provide a simple and compact transformer of the 30 moving-coil type by means of which very close regulation of the current supplied by the secondary member may be had. A trans-former having this characteristic is espe-cially desirable for use in connection with 35 motion-picture machines. Many moving-picture machines now in use are equipped with incandescent lamps which demand close regulation of the current passing through them in order that the highest degree of effi-40 ciency may be obtained.

In pursuance of the above object, I pro-45 pose a moving-coil transformer in which one of the coils, hereinafter designated as the sec-ondary coil, for purposes of convenience 50 only, is stationary with respect to a core member, while the primary coil is adapted for movement away from, and toward, the aforesaid secondary coil. Furthermore, I find that, if the moving coil be pivoted and 55 restrained in its movement by a particular means, which I shall hereinafter more fully describe, a very close regulation of the cur-60 rent furnished by the secondary coil may be obtained. I preferably employ a resilient 65 restraining means and so adjust the con-

stant thereof that the restraining force ex-60 erted thereby shall vary in the same degree as the moment of the pivoted coil, the mo-ment of the coil in question increasing, of course, as the coil moves farther away from 65 its normal position; that is, the position in which it is in juxtaposition to, and inductively interlinked with, the secondary coil. So far as I am aware, no such restraining means has heretofore been suggested for use 70 with transformers of this type.

The expression "moment of the coil" as 75 used throughout this specification and in the attached claims refers to the gravitational component of the forces tending to move the 80 coil multiplied by the horizontal distance between the center of gravity of the coil and the point about which the coil pivots.

As above pointed out, regulating means 85 of the type suggested are of particular bene-fit in the motion-picture field, and it should be noted that it is now common practice for motion-picture houses to employ two pro-jection machines, the machines being used 90 alternately; that is, one machine is employed for projection purposes while the film upon the other machine is being rewound and, if desired, properly focused. A further object of my invention, therefore, is to provide 95 regulating means of such character that both the current required for the projecting ma-chine, as well as that necessary for the pur-pose of focusing the other machine upon 100 which the film is being rewound, may be furnished from one transformer.

Difficulty has been experienced heretofore, 105 however, in accomplishing the above object on account of the instability occasioned when two independent currents of different volt-ages are drawn from a constant-current 110 transformer. In the structure which I shall hereinafter describe, and the one which I consider most desirable for furnishing power to projection machines, I believe that the derivation of two independent currents would render the operation of the moving coil out of the question unless a particular winding arrangement were employed. In the hereinafter described structure, therefore, I have provided a coil structure which is wound in such manner that, although a smaller auxiliary secondary member is used to supply current at a low voltage to the lamp in that machine, the film in which is being rewound, for focusing purposes, there

is no appreciable repulsion occasioned by the additional ampere turns which are set up when the current passes through this secondary coil. I accomplish this result by 5 winding the auxiliary secondary coil in close inductive relation to, and preferably upon the same coil frame as, the primary member. The manner in which this obviates the above-mentioned difficulty will be herein- 10 after more specifically pointed out.

Referring more particularly to the drawing, and especially to Figs. 1 and 2, a casing 1 is provided with lugs 2 and 3 upon which is supported a core member 4 comprising 15 three core legs 5, 6 and 7 and end yoke members 8 and 9. Embracing the middle leg 6 are members 10 and 11. The member 10 comprises a cylindrical spool 12 and a main primary coil 13, and the member 11 comprises a cylindrical insulating spool 14 and a main secondary coil 15. For purposes of convenience and for promoting the clarity of illustration, I have not shown the manner in which the various coils are interconnected. 20 However, reference to Fig. 4 will make clear the manner in which I connect the various coil units, it being noted that I have shown an auxiliary secondary coil 16 connected in series relationship with the main secondary 25 coil 15. In Fig. 2, the auxiliary secondary coil 16 is shown as wound outside of the main primary coil 13. The reason for this specific association of coils will hereinafter be more fully described.

30 The structure of the insulating cylinder 12 of the coil member 10 projects beyond the latter at both ends of the winding 13 and thereby furnishes a cylindrical seat to which are secured arms 17, 18, 19 and 20. At right 35 angles to the arm members 17 and 18, and formed integrally therewith, is a beam member 21. The arm members 19 and 20 are united and extended downwardly to form a member 22 which is carried upon an axle 23 journaled in upstanding lugs 24. It will be 40 noted that the structure comprising members 17, 18 and 21, together with the connection thereof to the cylindrical insulating member 12, the arms 19 and 20, and the member 22 constitute a pivotally mounted frame or carriage for the member 10 which is adapted to be moved in such manner that the member 10 may assume a position which is in angular relation to its normal position, 45 although it continuously embraces the middle core leg 6. It will be observed that such pivotal movement and the subsequent angular disposition of the member 10 results in a greatly increased leakage path for the flux 50 which is generated by the ampere turns of the respective windings.

Resilient restraining members 25 and 26 have corresponding ends secured to the ends of the beam 21 and their other ends secured 55 in spring-engaging means 27 and 28, respec-

tively, the last-named means being pinned to a shaft 29 which is journaled in lugs 30 and 31 projecting from the sides of the casing 1. Likewise, rigidly pinned to the shaft 29 is an adjusting arm 32 which is adapted to move 70 over, and be secured in, an arcuate notched engagable member 33. It will be noted that, by reason of the rigid connection of the members 27 and 28, as well as the adjusting arm 32, to the shaft 29 a movement of the latter downwardly to the right will result in an increase in the tension of the spring members 25 and 26.

In order to eliminate the shock which might otherwise occur when the moving coil 10 is repelled rapidly from the coil 11, a buffer member 34 and associated buffer post 35 are provided.

Referring now more particularly to Fig. 4, and observing, in this connection, the structure shown in the lower right-hand corner of Fig. 2, the main primary coil 13, the main secondary coil 15 and the auxiliary secondary coil 16 are shown as connected to two incandescent lamps 36 and 37 through a 90 double-pole, double-throw switch 38 having the switch points *a*, *b*, *c*, and *d* and the terminals *e* and *f*. In this figure, I have used the lamps 36 and 37 for purposes of illustration and wish it to be understood that 95 they represent, in consistency with other portions of the description of my invention, projection machines, and further that, as hereinbefore set forth, it is usual for one of the machines to be used for projecting purposes, while the film is being rewound in the other machine, the latter being, at the same time, focused, if desired. While the specified operation and focusing of the machines represented by lamps 36 and 37 constitutes no part of my invention, I have, nevertheless, shown individual switches 39 and 40 by means of which either unit may be cut off from the source of current supply, if so desired. A more specific description of 100 the function of the particular connections shown, when applied to motion-picture service will be given in the following description of the operation of my transformer.

In the ensuing description, Fig. 3 should 115 be referred to. In this figure, I have shown, graphically, the manner in which the magnetic repulsive effect between the two coils, the consequent divergence of the coil 10 from its normal position, and the restraining force 120 of the spring members 25 and 26, are associated.

Inasmuch as I desire to maintain constant current in the secondary circuit which is derived from the main secondary coil 125 member 15, it is essential that, should the current in this member tend to increase, an increased magnetic leakage would immediately occur in order that the current through the consumption apparatus be maintained 130.

at a constant value. In order to accomplish this, I find it necessary to provide a restraining force for the moving member 10 which shall increase in exactly the same degree as the moment of the member 10 about its pivotal point of support. Therefore, I select spring members 25 and 26 having such constants that, as they are successively lengthened by the increased force 10 due to the increasing moment arm of the member 10, the moment of the latter is exactly neutralized by the restraining force of the spring members.

Referring to Fig. 3, the distance OX represents the force caused by the repulsion of the member 10 for the member 11. The line OY represents the increase of the gravitational component of the member 10 as it moves farther out of vertical alignment 20 with its pivotal point. The line XY' represents the increasing force exerted by the spring members 25 and 26 as the member 10 moves about its axis, thus elongating said spring. By a suitable choice of 25 springs, the curves OY and XY' may be made of exactly opposite equal slopes. If these members have equal but opposite slopes, the algebraic resultant thereof will be a constant force or that represented by 30 the vertical distance between the lines OO' and XX'. In this manner, the effect of the gravitational component tending to move the member 10 is eliminated.

If a higher or lower constant secondary 35 current is desired, suitable adjustment of the arm 32 will either increase or decrease the initial spring tension. An adjustment providing an increased initial spring tension is denoted by the spring tension line 40 ZY'' which is, of course, parallel to the spring tension line XY'. The resultant constant force between the forces represented by OY and ZY'' equals the vertical distance between the lines OO' and 45 ZZ'. The line OY, if sufficiently extended, would become a sine wave, but for the small range of movement here employed, it is substantially a straight line. As the line OY is straight, the increase in the moment of 50 the coil would be exactly proportional to the amount of movement thereof.

As hereinbefore pointed out, another object of my invention is to provide unitary transforming and current-regulating means 55 whereby one load,—in this case a projecting machine may be supplied with full voltage,—while another load,—in this case a projecting machine in which it is desired to correct the focus,—is being supplied with 60 a different voltage. Moreover, it is desirable that the ampere turns of the various windings supplying such voltages be so adjusted that either machine may be supplied independently with either voltage, that is 65 to say, it may at times be necessary to run

only one machine and, in such circumstances, it is desirable to have available a source of full voltage for projecting purposes as well as a source of approximately half voltage for use in obtaining the correct focus. In this connection, it may be mentioned that some difficulty has been experienced heretofore in obtaining the proper voltage for the two purposes specified because, when focus correction was being carried out, either resistance had to be inserted in the circuit or it was necessary to arrange a number of taps on the secondary member. In either case, complications arise, and moreover, it is apparently impossible, with 80 either of the last-mentioned methods, to operate an automatic constant current regulating transformer with both of the secondary coils active.

I propose, therefore, to connect the main 85 secondary coil, shown in Fig. 2 at 15, in series with the auxiliary coil 16 and to closely interlink the auxiliary secondary winding and the main primary winding. By so inductively arranging the various 90 windings, I am able to neutralize the additional ampere turns which are set up by the auxiliary secondary winding and to prevent, therefore, the added repulsion which would occur if the two secondary windings 95 were placed on the same coil. Were the latter arrangement used, any attempt to derive current from the two secondary members simultaneously would result in an increased repulsion and a consequent derangement of the required constant-current conditions.

Where the arrangement above described is used, however, I find that the increased ampere turns which the auxiliary winding sets 105 up are immediately neutralized by the opposing ampere turns which its operation occasions in the main primary winding, and, therefore, no increased repulsive effect is set up even though current is derived from both 110 secondary coils simultaneously. This effect is promoted by the very close inductive interlinkage of the auxiliary secondary coil with the main primary coil, since substantially no leakage occurs between the two. 115

As is illustrated in Fig. 4, a tap connection is brought from between the two secondary members and connected between the two machines. Assuming that the double-pole switch is in the position shown by the dotted lines, a tracing of the circuits discloses the fact that the main secondary winding 15 furnishing full voltage to the lamp 37 while the auxiliary winding 16 is furnishing substantially one-half voltage to the lamp 36. With 120 the conditions shown, the machine with which lamp 37 is used would be employed to project motion pictures upon the screen, while the lower-intensity lamp 36 is furnishing just enough light in its associated ma- 130

chine to enable the operator properly to determine the correct focus. It will be observed, therefore, that I have provided, in one structure, requiring the use of a simple 5 transfer switch only, such inductively interlinked windings as will enable two machines to be operated intermittently, there always being the correct conditions present for the use of one machine as a projecting 10 unit, while the focus of the other machine is being arranged.

I further contribute to the compactness and the simplicity of a regulating transformer of the character described by placing 15 the aforesaid transfer switch in the position shown in the lower right-hand corner of Fig. 2. All of the operating mechanism, therefore, is enclosed within a fire-proof casing, the switch being operated by a handle 20 38^a which projects outside of the casing.

Referring now to Figs. 5 and 6, which are fragmentary views illustrating modifications of the pivotal mounting 24, I have shown, in the former figure, a pivotal mounting 25 which I consider extremely desirable in transformers of the heretofore-described type. The downwardly extending member 22 is bolted to the axle 23, and the entire structure is mounted upon a resilient member 42. It will be observed that this member 42 is secured to the base of the transformer casing to the left of a vertical axis 30 passing through the normal position of the member 10. Therefore, as the latter departs 35 from normal, the axle 23 will roll to the left along the resilient member 42, which, by reason of its being secured to the axle, will coil thereabout. I find that such a pivotal mounting is productive of little or no frictional 40 losses and, therefore, I find its use very desirable in regulators requiring the degree of accuracy heretofore described.

In Fig. 6, I have illustrated an alternative 45 method of providing a resilient restoring force for the moving coil. In this modification, I employ a coiled spiral spring 43 and so secure it to the lug 24 and the carriage member 22 that the moment of the moving coil is constantly nullified by the increased 50 tension of the coil spring. I find that, in some cases, this construction simplifies the regulating transformer, to some extent, but the form of retaining spring shown in Fig. 2 is probably more easily adapted for adjustment.

While I have illustrated but one form of 55 my invention, I desire that no unnecessary limitations shall be placed thereupon and that it be restricted only by the showing of the prior art or by the scope of the appended claims.

I claim as my invention:

1. A core member, coil members inductively associated therewith, one of said coil

members being mounted for pivotal movement, and restraining means so opposing the movement of the pivoted coil member that a constant force operates to return said member to normal position.

2. A core member, coil members inductively associated therewith, one of said coil members being mounted for pivotal movement, and restraining means opposing the movement of the pivoted coil member and having an effective returning force which is 75 constantly equal to the gravitational moment of the pivoted coil member when it moves from normal position.

3. A core member, coil members inductively associated therewith, one of said coil members being mounted for pivotal movement, and resilient restraining means opposing the movement of the pivoted coil member and having a returning force that varies 80 in the same proportion as the gravitational moment of said pivoted coil member when the latter departs from normal position.

4. A core member, primary and secondary coils inductively associated with, and spaced apart on, said core member, one of said coils 90 being pivotally mounted and adapted to be moved away from the other coil by the magnetic repulsion therebetween, and resilient means opposing said movement, the restraining force thereof varying directly 95 as the gravitational moment of said pivotal coil whereby a constant force opposes the divergence of said coils.

5. A core member, primary and secondary coils inductively associated with, and spaced apart on, said core member, one of 100 said coils being pivotally mounted and adapted to be moved away from the other coil by the magnetic repulsion therebetween, resilient means opposing said movement, the 105 restraining force thereof varying directly as the gravitational movement of said pivotal coil whereby a constant force opposes the divergence of said coils, and means for varying the amount of said constant opposing 110 force.

6. A core member, primary and secondary coils inductively associated with, and spaced apart on, said core member, means for pivotally mounting one of said coils, and resilient 115 restraining means associated with said pivotal mounting means and having a returning force that varies in the same proportion as the gravitational moment of said pivotally mounted coil.

7. A core member, primary and secondary coils inductively associated with, and spaced apart on, said core member, means for pivotally mounting one of said coils comprising a frame member carrying said coil 125 and members furnishing journaled supports for said frame, and a coiled resilient member attached to said frame and having a re-

turning force that varies in the same proportion as the gravitational moment of said pivotally mounted coil.

8. A core member, primary and secondary coils inductively associated with, and spaced apart on, said core member, a flexible member, means for pivotally mounting one of said coils comprising a frame member for carrying said coil mounted on said flexible member, said flexible member being adapted to rotate with said frame member and thereby furnish a substantially frictionless support for the moving coil.

9. A core member, primary and secondary coils inductively associated with, and spaced apart on, said core member, a flexible member, means for pivotally mounting one of said coils comprising a frame member for carrying said coil mounted on said flexible member, said flexible member being eccentrically secured with respect to a vertical line through the point of support of said moving coil and being thereby adapted to provide a substantially frictionless support for said coil.

10. A core member, primary and secondary coils inductively associated with, and spaced apart on, said core member, a flexible member, means for pivotally mounting one of said coils comprising a frame member for carrying said coil mounted on said flexible member, said flexible member being eccentrically secured in the direction of inclination of said movable coil and adapted to impart a rolling motion to the support of said coil.

11. A core member, primary and secondary coils inductively associated with, and spaced apart on, said core member, one of said coils being pivotally mounted and adapted to be moved away from the other coil by the magnetic repulsion therebetween, resilient means opposing said movement, the restraining force thereof varying directly as the gravitational moment of said pivotal coil whereby a constant force opposes the divergence of said coils, and an auxiliary secondary winding so associated with the main primary and secondary coils that no additional repulsive effect is exerted therebetween when said auxiliary secondary winding is loaded.

12. A core member, primary and secondary coils inductively associated with, and spaced apart on, said core member, one of said coils being pivotally mounted and adapted to be moved away from the other coil by the magnetic repulsion therebetween, resilient means opposing said movement, the restraining force thereof varying directly as the gravitational moment of said pivotal coil whereby a constant force opposes the divergence of said coils, and an auxiliary secondary winding so associated with the main primary and secondary coils that no appreciable magnetic

leakage occurs between the main primary 65 coil and the auxiliary secondary coil.

13. A core member, main primary and secondary coils having a loose inductive relation to each other and associated with said core member, the primary coil being adapted 70 for movement away from the other coil by the magnetic repulsion therebetween, and an auxiliary secondary coil wound, and adapted to move, with said main primary coil, whereby no additional repulsive effect between the main primary and secondary coils 75 is exerted.

14. A core member, main primary and secondary coils having a loose inductive relation to each other and associated with said 80 core member, one of said coils being adapted for movement away from the other coil by the magnetic repulsion therebetween, an auxiliary secondary coil having a close inductive relation to said main primary coil, 85 whereby no additional repulsive effect between the main primary and secondary coils is exerted, and switching means whereby said secondary windings may independently and simultaneously supply different loads. 90

15. A core member, main primary and secondary coils having a loose inductive relation to each other and associated with said core member, one of said coils being adapted 95 for movement away from the other coil by the magnetic repulsion therebetween, an auxiliary secondary coil having a close inductive relation to said main primary coil, whereby no additional repulsive effect between the main primary and secondary coils 100 is exerted, connections whereby said main secondary member may simultaneously supply one load and said auxiliary secondary member another load, and switching means for reversing the connections. 105

16. In a current-regulating transformer, a core member, a stationary coil member and a pivoted movable coil member having a loose inductive relation to each other, one of said coils consisting entirely of secondary 110 turns and the other coil consisting of both primary and secondary turns, and resilient restraining means for governing the movement of said movable coil, the restraining force of which varies in the same proportion 115 as the gravitational moment of the movable coil about its support.

17. In a current-regulating transformer, a core member, a stationary coil and a pivoted movable coil having a loose inductive 120 relation to each other, one of said coils consisting entirely of secondary turns and the other coil consisting of both primary and secondary turns, resilient restraining means for governing the movement of said movable coil, the restraining force of which varies in the same proportion as the gravitational moment of the movable coil about 125

its support, and means for varying the restraining force of said resilient means.

18. In a current-regulating transformer, a core member, a stationary coil member and a pivoted movable coil member having a loose inductive relation to each other, one of said coils consisting entirely of secondary turns and the other coil consisting of both primary and secondary turns, resilient restraining means for governing the movement of said movable coil, the restraining force of which varies in the same proportion as the gravitational moment of the movable coil about its support, and means for varying the restraining force of said resilient means comprising spring-engaging means, a journaled member to which the engaging means are secured, means secured to said journaled member for moving the same to vary the spring tension, and means for securing the last-named means in a predetermined position.
19. In a current-regulating transformer,

a core member, a stationary coil member and a pivoted movable coil member having a loose inductive relation to each other, one of said coils consisting entirely of secondary turns and the other coil consisting of both primary and secondary turns, resilient restraining means for governing the movement of said movable coil, the restraining force of which varies in the same proportion as the gravitational moment of the movable coil about its support, means for varying the restraining force of said resilient means comprising spring-engaging means, a journaled member to which the engaging means are secured, means secured to said journaled member for moving the same to vary the spring tension, and notched arcuate engageable means for securing the last-named means in a predetermined position.

In testimony whereof, I have hereunto subscribed my name this 11th day of June, 1919.

ALFRED L. ATHERTON.
